United States Patent Office

Des. 185,903
Patented Aug. 18, 1959

185,903

VEHICLE SEAT

Chester J. Barecki, Grand Rapids, Mich., assignor to American Seating Company, Grand Rapids, Mich., a corporation of New Jersey

Application January 22, 1959, Serial No. 54,263

Term of patent 14 years

(Cl. D15—8)

The broken lines shown in Figures 1 and 2 are for illustrative purposes only.

I claim:

The ornamental design for a vehicle seat, substantially as shown and described.
